(57) **CLAIM**

I claim the ornamental design for "hose winding device with crank," as shown and described.

DESCRIPTION

FIG. 1 shows a perspective view of a hose winding device with crank;

FIG. 2 shows a right-hand lateral view of the hose winding device with crank of FIG. 1;

FIG. 3 shows a left-hand lateral view of the hose winding device with crank of FIG. 1;

FIG. 4 shows a rear view of the hose winding device with crank of FIG. 1;

FIG. 5 shows a front view of the hose winding device with crank of FIG. 1;

FIG. 6 shows a top view of the hose winding device with crank of FIG. 1; and,

FIG. 7 shows a bottom view of the hose winding device with crank of FIG. 1.
